Patented Sept. 12, 1922.

Inventor

Frederic Timmerman

By James C. Ledbetter Attorney

UNITED STATES PATENT OFFICE.

FREDERIC TIMMERMANN, OF NEW YORK, N. Y.

SPRING COMPRESSOR.

Application filed December 3, 1920. Serial No. 427,933.

To all whom it may concern:

Be it known that I, FREDERIC TIMMERMANN, a citizen of the United States of America, residing at New York, borough of Manhattan, in the county of New York and State of New York, have invented certain new and useful Improvements in Spring Compressors, of which the following is a specification.

10 This invention relates to valve handling tools and more particularly to spring compressors.

An object of the invention is to produce improvements in valve compressors to the end that this tool may be used for compressing a spring to facilitate the removal thereof from automobile engines so that the poppet valves of an internal combustion motor may be expeditiously removed 20 and replaced.

Among the several objects of my invention I have in view the production of a spring compressor tool which clamps or compresses a spring and holds it in that 25 position while the spring is removed and until the spring is replaced, whereupon the tool releases its hold to permit the spring to expand into its original position.

Referring to the accompanying drawings forming a part hereof, Figure 1 shows 30 the spring compressing tool in side elevation with a spring in position to be compressed.

Figure 2 illustrates a front view of the 35 tool with the spring locked in the tool and being in compressed position.

Figure 3 shows a sectional view of the 40 spring compressor as taken on the line 3—3 of Figure 2.

Figure 4 illustrates a cross-sectional view taken on the line 4—4 of Figure 2.

A spring compressor tool constructed in accordance with the plans of my invention embodies a casing with a spring seat or support on one end and a slide confined in 45 the other end. A toggle mechanism is employed to move the slide up and down to compress and release the spring.

Referring now more in particular to the 50 drawings for a description of the parts of the invention, there is shown a casing 6 made round or partly cylindrical in form with one side left open to receive a coil spring to be compressed. The casing is 55 made with a flange or support 7 on one end

thereof by turning inwardly the end of the casing. The outer parallel edges of the casing are turned inwardly to form guides 8. A slot 9 is formed vertically in the casing to admit and guide a pin or stud used to 60 transmit motion to the compressor part, as later described.

A slide 11 is made similar in form to the casing 6 except that it is shorter and slightly smaller in size to fit into the casing with 65 its outer parallel edges slideably confined in the guides 8 so as to maintain the slide in proper position during its reciprocal motion in the casing. The upper end of the slide is made with a flange 12 turned inwardly similar to the flange or support 7 made on the other end of the casing 6.

A wheel, or in fact a crank, is journaled on a suitable bearing anchored on one end of the casing 6 and this crank preferably 75 comprises a socket-hub 14, integrally formed with spaced flanges 15. One end of a link 16 is confined between the flanges 15 and connected thereto by a journal pin 17. The other end of this link is pivotally connected 80 with a pin or stud 18 which is confined in the slot 9 and anchored to the slide 11.

A key or hand tool 20 has a square or hexagonal ball-shaped end 21 and may be inserted into the socket-hub 14 whereby the 85 wheel or crank 14—15 is rotated. The key 20 is made with the ball-shaped end 21 so that it may be inserted into the socket 14 at an angle to enable a mechanic to more conveniently work at the tool and operate 90 the toggle linkage 14—16 from most any position.

By rotating the crank 15, a motion is transmitted through the link 16 to the slide 12 which reciprocates the said slide in the 95 casing. In the use of the compressor, the mechanic moves the slide to its uppermost position and slips the casing over the coil spring until the spring is confined in the casing as shown in Figure 1 with the flanges 100 7 and 12 engaging coils of the spring. The key 20 is then turned which draws the slide 11 toward the flange 7, thus compressing that portion of the coil spring confined between the two flanges 7 and 12. The crank 105 15 is rotated somewhat more than 180 degrees so that the point of link connection 17 passes the line of center of action in the toggle mechanism, whereby the slide 11 is locked in its lowermost position and will 110

not permit the spring to expand when the key 20 is removed from the socket of the crank.

With this character of spring compressor, 5 it is possible to easily remove a valve spring from an internal combustion motor and leave it in the tool until the spring is replaced, whereupon the key is again used to rotate the crank or wheel 15 until the compression of the spring acts to open up the device to permit the spring to expand to its original set position.

An additional feature of this tool resides in the ability of the casing 6 to hold 15 the compressed spring in position to prevent it from bulging out from its compressed center which so often happens with many other types of devices. The spring is held in straight and aligned position 20 within the casing during the time that it is under compression.

Having thus described the construction and operation of a spring compressor constituting an embodiment of my invention, 25 what I desire to claim and secure by Letters Patent is:

1. A spring handling and compressor tool comprising a pair of spring grip members movable one in relation to the other, a link 30 having one end pivotally attached to one of the aforesaid members, and a rotatable device journaled on the other member and having pivotal connection with the other end of the aforesaid link, the said link being 35 curved so as to swing around the axis of the rotatable device with the middle portion thereof engaging the rotatable device so as to effect a locked position to hold a spring compressed, and handle means related with 40 the rotatable device to operate the tool.

2. A spring compressor comprising a frame, a slide confined and movable in the frame, a link connected with the slide, a rotatable member connected with the link to 45 actuate the slide, said rotatable member provided with a socket, and a handle arranged to engage the socket to operate the rotatable member.

3. A spring compressor tool comprising a 50 frame to encompass and hold a spring in alignment while being compressed, a slide movable in relation to the frame and adapted to engage a spring to compress it, a device to move the slide, a handle carried by the 55 compressor tool to operate the device, and the said handle having a universal connection established with the tool so that an operator may stand at a selected position of advantage and actuate the tool from any 60 angular position.

4. A spring compressor tool comprising a 65 frame to encompass and hold a spring in alignment while being compressed, a slide movable in relation to the frame and adapted to engage and compress a spring, said

tool being provided with a detachable handle so that the tool in use may first have its frame and slide set up against a valve spring in an engine, after which the handle is inserted to work the tool from any angle.

5. A spring compressor comprising a device constructed in the form of a casing to partly surround the coils of a spring to be compressed, a slide movably confined in the casing, a flange made on the casing and on 70 the slide to engage and hold a spring, a rotatable member journaled on the frame, a curved toggle link connection established between the slide and rotatable member, and a handle carried by the rotatable member to 75 move the curved link into a locked position whereby the slide is moved to compress the spring.

6. A spring compressor tool comprising a 80 casing to encompass a spring to be compressed, a flange or support made on one end of the casing to engage the spring, the outer parallel edges of the casing bent over to form a guide, an actuator device slideably retained in the guides, a flange made on the 85 actuator device to engage the spring to be compressed, and a toggle linkage arranged to move the actuator device against the pressure of the spring to compress said spring and hold it locked in compressed position, 90 and a detachable key extending at right angles out from the tool to operate the slide.

7. A spring compressor tool comprising a frame and slide to engage a spring and move 95 relatively one on the other, a rotatable socket member journaled on the tool, a link having one end attached to the slide and the other end attached to the frame, and a handle engaging the rotatable socket member to turn the member to actuate the link 100 and slide.

8. A spring compressor tool comprising a 105 frame and slide movable one in relation to the other, a rotatable member journaled on the tool, a curved link connecting the slide 110 and rotatable member, and a handle to revolve the member to draw on the curved link to force it down and partly around the journal of the rotatable member to effect a locked position of the frame and slide to clamp the 115 spring in compressed position.

9. A spring compressor tool comprising a 120 frame and slide movable one in relation to the other, a wheel journaled on the tool, a curved link connecting the slide with the periphery of the wheel, said wheel provided with a groove made therein to receive the curved link, and a handle to rotate the wheel whereby the curved link passes into the 125 groove and partly around the wheel journal to lock the slide in downwardly limited position.

10. A spring compressor tool comprising a 130 frame and slide movable in relation one to the other, a journal pin anchored to the tool,

a device in the nature of a crank rotatably carried on the journal pin, a link having one end attached to the slide and the other end attached to the crank device, and a handle to 5 turn the crank whereby the link moves into contiguous position with the journal to effect

a locking relation between the slide and frame to hold a spring in compressed position.

In testimony whereof I hereunto affix my 10 hand, this 24th day of November, 1920.

FREDERIC TIMMERMAN.
